(57) **CLAIM**

The ornamental design for an expandable mobile building, as shown and described.

DESCRIPTION

FIG. 1 is a front perspective view of the expandable mobile building

FIG. 2 is a rear perspective view of the expandable mobile building.

FIG. 3 is an underside front perspective view of the expandable mobile building.

FIG. 4 is a front view of the expandable mobile building.

FIG. 5 is a rear view of the expandable mobile building.

FIG. 6 is a left view of the expandable mobile building.

FIG. 7 is a closed position front perspective view of the expandable mobile building.

FIG. 8 is a closed position rear perspective view of the expandable mobile

FIG. 9 is a closed position underneath front perspective view of the expandable mobile building.

FIG. 10 is a closed position front view of the expandable mobile building.

FIG. 11 is a closed position rear view of the expandable mobile building.

FIG. 12 is a closed position right view of the expandable mobile building; and,

FIG. 13 is a closed position top view of the expandable mobile building.
